APPARATUS FOR FEEDING A PLURALITY OF
MOTOR FUELS

Edmund E. Hans, Detroit, Mich.

Application June 6, 1938, Serial No. 212,063

7 Claims. (Cl. 221—67)

This invention relates to the feeding of a plurality of motor fuels to an internal combustion engine, and more particularly to apparatus for completing said feeding. In my application Serial No. 199,517 filed April 1, 1938, there is disclosed means for automatically bringing about harmonious action of an internal combustion engine through the use of motor fuels of variant characteristics, i. e., by the use of two fuels such as gasoline and alcohol. The present invention sets forth the dual fuel tanks and apparatus for simultaneously filling the fuel tanks.

The principal object of the present invention is to provide new and improved apparatus for containing two fuels of variant characteristics and means for simultaneously filling said apparatus.

Another object is to provide new and improved dual nozzles having variant nozzle openings to correspond to the openings in a dual fuel tank so that the user will not become confused and intermix the fuels when filling the tanks.

A further object of the present invention is to provide a new and improved filler cap for a dual fuel tank so constructed that it will tightly seal both openings in the tank.

A still further object of the present invention is to provide a hinged tab for one of the openings in said dual fuel tank, the same being of a distinctive color to indicate what fuel is to be injected into that particular tank.

The above and other objects will appear more fully from the following more detailed description, and from the drawing, wherein

Fig. 1 is a top plan view of a tank showing the top openings therein;

Fig. 2 is an end elevation of a tank, partly in section;

Fig. 3 is a plan view of a filler cap, partly broken away;

Fig. 4 is a cross section of a cap and filler cap flange taken substantially on the line 4—4 of Fig. 3;

Fig. 5 is a cross section of the filler cap flange taken substantially on line 5—5 of Fig. 3;

Fig. 6 is a sectional elevation of a dual gasoline pump;

Fig. 7 is a detail of the filler nozzles for filling the tank showing in Fig. 1;

Fig. 8 is an enlarged view of the nozzles shown in Fig. 7; and

Fig. 9 is an end view of the nozzles shown in Figs. 7 and 8.

Referring now to the drawing, the numeral 12 designates a fuel tank of any well known shape having a wall 13 formed therein to divide the tank 12 into two separate compartments, for the reception of two fuels of variant characteristics, such as gasoline in the larger compartment 14, and alcohol in the smaller compartment 15.

Each compartment of the tank 12 is provided

with means for conducting the two fuels herein designated to the carburetor, tube 16 leading from the alcohol compartment 15 and tube 17 leading from the gasoline compartment 14 through cap 18. To fill both compartments of tank 12 simultaneously there is provided an opening so placed that wall 13 acts as a barrier therebetween and a semi-circular opening is provided on each side of the barrier so that fuel may be deposited into compartments 14 and 15. A flange 19 is provided to align with the opening in the top of tank 12, the same being designed to provide an engaging means for a filler cap 20. Flange 19 is of circumferential design and has formed therein a web 21 which runs diametrically across the inside of flange 19 and is so aligned that the same may be soldered to the top of wall 13 to form a barrier between openings 22, 23, into compartments 14, 15. Web 21 extends the full height of flange 19, and when filler cap 20 engages flange 19 in sealed relationship, prevents the intermingling of gasoline and alcohol, when the vehicle is in motion. Flange 19 is also grooved as at 24 to receive a pair of ears 25, 26, secured to the inner portion of filler cap 20 by means of securing means 27, 28, ears 25, 26, are bent downwardly away from the top of the cap 20 sufficiently to engage grooves 24 when the cap 20 is turned in a clockwise direction to lock the same to flange 19 the ears passing into the grooves to hold the cap in locked engagement. A gasket 29 is cut to conform to the shape of flange 19 and is interposed between flange 19 and filler cap 20 to form a tight seal. A tab 30 is pivotally secured to the side of flange 19 by means of a pin 31 having a spring mounted thereon and having one extremity thereof bent as at 32 to form a rest to maintain tab 30 normally in position shown in Fig. 4 of the drawing. Tab 30 may be brightly colored to act as an indicator to the filling station attendant and warn him as to which fuel is to be injected into the tank in which the tab is placed. When the nozzles shown best in Figs. 7 and 8 of the drawing are inserted into the openings 22, 23, one of said nozzles may also be colored a color corresponding to that of the tab to avoid confusion on the part of the attendant. When the nozzle is inserted tab 30 will move downwardly from its normal horizontal position shown in Fig. 4 to allow insertion of the nozzle into the flange opening.

To aid the distribution of two different fuels there is also provided a new and unique distribution pump consisting of a base 33, an upright supporting member 34 terminating in a horizontal supporting member 37 adapted to support a pair of fuel supply tanks 35, 36, one to contain gasoline and the other alcohol. These fuels are pumped to tanks 35, 36 through conduits 38, 39 located in supporting member 34. Filling hose 60

40, 41 are also provided to communicate with tanks 35, 36 and supply fuels to twin dual nozzles 42, 43 which are constructed as a unit and held together by means of brace 44. A control means 5 45 is provided on each nozzle to allow one-handed operation of the nozzles by the station attendant, and one nozzle is constructed much smaller than the other in order to feed gasoline into tank 14 much faster than nozzle 43 feeds alcohol to tank 10 15 in order to finish the filling of both tanks simultaneously. As will be seen from Fig. 9 of the drawing nozzle opening for nozzle 42 is much larger than the nozzle opening for nozzle 43, and to correspond and register therewith, opening 22 15 which leads into gasoline compartment 14 is much larger than opening 23 which leads into alcohol compartment 15, which construction will greatly aid the filling station attendant so that it would be practically impossible for him to 20 switch the nozzles and inject alcohol into the gasoline compartment, or vice versa.

There has been provided herein new and improved means for carrying a plurality of motor fuels, as well as new and improved means for 25 pumping said fuels into the unique carrying device. Taken in conjunction with my improved method of injecting a plurality of fuels into an internal combustion engine the complete disclosure sets forth a new and novel construction.

30 Although the invention has been described as applied to a specific installation, it is understood that certain variations and modifications may be employed without departing from the fundamental principles as indicated by the scope of the 35 following claims:

I claim:

1. A fuel system for internal combustion engines comprising a plurality of fuel tanks, a filler neck disposed adjacent to said tanks, said filler 40 neck having a plurality of passageways therein which lead to said fuel tanks, respectively, a plurality of nozzles fixed together to be handled as a single unit, conduits extending from different fuel supply sources to said nozzles, respectively, said nozzles each being adapted to enter one of said filler neck passageways, and means co-acting with said nozzles and said filler neck for establishing a pre-determined relationship therebetween so that each of said nozzles may enter into only one particular filler neck passageway, for the purpose described.

2. A fuel system for internal combustion engines comprising a plurality of fuel tanks, a filler neck disposed adjacent to said tanks, said filler 55 neck having a plurality of passageways therein which lead to said fuel tanks, respectively, the filler neck end of said passageways being of dissimilar shape, a pair of nozzles fixed together so as to be handled as a unit, and conduits extending from two different fuel supply sources to said nozzles, respectively, said nozzles being shaped similar to said filler neck passageways and positioned so that they may simultaneously enter only their respective filler neck passageways.

60 3. A fuel system for internal combustion engines comprising a plurality of fuel tanks, a filler neck disposed adjacent to said tanks, said filler neck having a plurality of passageways therein which lead to said fuel tanks, respectively, one of the filler neck ends of said passageways being substantially larger than the other, a pair of nozzles fixed together to be handled as a single unit, and a conduit extending from two different fuel supply sources to said nozzles respectively, 70 said nozzles being of shape and size similar to

said filler neck passageways, respectively, and so positioned that the larger of said nozzles may enter the larger passageway but cannot enter said smaller passageway.

4. A fuel system for internal combustion engines comprising a plurality of fuel tanks, a filler neck disposed adjacent to said tanks, said filler neck having a plurality of passageways therein which lead to said fuel tanks, respectively, the filler neck ends of said passageways being of segmental shape with a common wall forming their flat sides, one of said segments being substantially larger than the other, a pair of nozzles fixed together to be handled as a single unit, and conduits extending from two different fuel supply 15 sources to said nozzles respectively, said nozzles each being of segmental shape and so proportioned and positioned that they may simultaneously enter the said respective filler neck passageways, the larger of said nozzles being prevented by its size from entering the smaller of the passageways.

5. A fuel system for internal combustion engines comprising a fuel container having a partition therein which forms two separate tanks, a common filler neck for both of said tanks, said filler neck having a plurality of passageways therein which lead to the respective tanks, the filler neck ends of said passageways being of dissimilar shape, a pair of nozzles fixed together so as to be handled as a single unit, and conduits extending from two different fuel supply sources to said nozzles respectively, one of said nozzles being shaped similar to one of said filler neck passageways and the other nozzle similar to the other passageway and spaced so that they may simultaneously enter said passageways, the last described nozzle being prevented by its shape from entering the first described passageway.

6. A fuel system for internal combustion engines comprising a main fuel tank, an auxiliary fuel tank disposed within said main tank, a common filler neck for both of said tanks disposed adjacent thereto, said filler neck having a plurality of passageways therein which lead to the respective fuel tanks, the filler neck ends of said passageways being of dissimilar shape, a pair of nozzles fixed together so as to be handled as a single unit, and conduits extending from two different fuel supply sources to said nozzles respectively, one of said nozzles being shaped similar to one of said filler neck passageways and the other nozzle similar to the other passageway, and spaced so that they may simultaneously enter said passageways, the shape of one nozzle preventing its use in the other of said passageways.

7. A fuel system for internal combustion engines comprising a main fuel tank, an auxiliary fuel tank disposed within said main tank, a filler neck disposed adjacent to said tank, said filler neck having a plurality of passageways therein which lead to the respective fuel tanks, the filler neck ends of said passageways being of unequal segmental shape with common flat sides, a pair of nozzles fixed together so as to be handled as a single unit, and conduits extending from two different fuel supply sources to said nozzles respectively, said nozzles being shaped similar to said filler neck passageways respectively so that they may simultaneously enter said passageways, the shape of one nozzle preventing its entrance into the other of said passageways.
